POWER-OPERATED DIRIGIBLE SPOTLIGHT
HAVING A SINGLE DRIVING MOTORJoseph H. Cone, Bridgeport, Conn., assignor to
Casco Products Corporation, Bridgeport, Conn.,
a corporation of Connecticut

Application April 22, 1949, Serial No. 88,972

12 Claims. (Cl. 240—61.9)

1

This invention relates to remote-controlled power-operated dirigible spotlights of the type commonly installed on automobiles, having a spot-light unit or lamp head mounted for turning about two non-parallel axes to obtain universal movement and therefore a wide angle or range of coverage.

One object of the invention is to provide an improved remote-controlled power-operated dirigible spotlight of the type mentioned, which has relatively few, inexpensive parts and is of simple and economical construction.

Another object of the invention is to provide an improved dirigible spotlight as above characterized, which may be very easily and accurately aimed or directed by an operator, without requiring the exercise of any considerable degree of skill.

A further and important object of the invention is to provide an improved power-operated, remote-controlled dirigible spotlight in accordance with the foregoing, wherein the lamp head or light unit when not being adjusted is held securely locked in position and prevented from shifting out of said position due to vibration, movement of the vehicle on which it is mounted, etc.

Still another object of the invention is to provide an electrically-controlled dirigible spotlight in accordance with the above, which is characterized by relatively few lead wires or connections between the spotlight and the control switch therefor.

A further object of the invention is to provide an improved dirigible spotlight having the foregoing characteristics, which is also extremely compact and of relatively small size and attractive appearance.

Yet another object of the invention is to provide a dirigible spotlight according to the foregoing, which is extremely sturdy in construction and reliable in operation throughout an extended period of use.

In accomplishing these objects I provide, in accordance with the invention, a lamp head or light unit mounted for turning about two non-parallel axes whereby an extremely large field or wide range of coverage is attained, and provide a motor and pair of drive mechanisms between the motor and light unit for turning the latter about the said axes respectively. One of said mechanisms preferably is permanently operative. In conjunction with this structure I provide means under the control of an operator for rendering the other of said drive mechanisms either operative or inoperative, and provide means operable in conjunction with said last-named means, for effecting reversal of the motor for either the operative or inoperative condition of said other drive mechanisms.

2

When both drive mechanisms are operative and the motor is turning in either direction, the turning of the light unit about one of its axes will be halted because of its rotation about the other axis. When the other drive mechanism is rendered inoperative, the operation of the permanently-operative drive mechanism will result in a turning of the spot-light unit about said one axis. Thus rotation about either axis may be effected independently of rotation about the other axis, and such rotation may be in either of opposite directions, depending on whether the motor is operating forward or in reverse. In consequence I have found that the aiming and directing of the spotlight may be very easily and quickly effected, even by one possessing a minimum amount of skill.

In the embodiment of the invention illustrated herein the drive mechanism rendered operative or inoperative includes a solenoid-operated clutch mechanism. The motor, to provide for reversibility, has a pair of field coils either one of which may be energized. By utilizing ground connections to the frame of the spotlight, and by interconnecting the solenoid and motor in a particular manner, I have found it possible to effect complete control and operation of the spotlight with no more than four lead wires extending between the light and the control switch, which latter is normally located at a remote point.

The drive mechanisms of the spotlight comprise bevel gears, spur gears and worm gearing so arranged that the various parts are extremely compact and the overall structure relatively small and not unpleasing in appearance. The parts are moreover few in number and of simple structure whereby a desirable economy of manufacture is attained.

The employment of a single, positive-type clutch, and of worm, spur and bevel gearing results in a sturdy construction which makes for reliability in operation.

Irreversible worm drives are provided in each drive mechanism, permanently connected with the lamp head whereby the latter is locked in any adjusted position when not being driven.

Other features and advantages will hereinafter appear.

50 In the drawings:

Figure 1 is a vertical sectional view through the improved spotlight of the invention, the lamp head being shown in part only.

Fig. 2 is a horizontal sectional view taken on line 2—2 of Fig. 1.

Fig. 3 is a vertical sectional view taken on line 3—3 of Fig. 2.

Fig. 4 is a fragmentary sectional view of a portion of the drive mechanism shown in Fig. 2, the clutch of the mechanism being disengaged, and

the engaged position of the clutch gear being indicated by a broken outline.

Fig. 5 is a schematic circuit diagram of the improved spotlight and control means thereof.

Fig. 6 is a horizontal sectional view through one type of control switch for the spotlight.

Fig. 7 is a view partly in elevation and partly in vertical section, through the switch of Fig. 6.

Fig. 8 is a view partly in section and partly in elevation, taken on line 8-8 of Fig. 6; and

Fig. 9 is a front elevational view of another type of control switch for the spotlight.

Referring to Figs. 1 through 3, the improved spotlight of the invention comprises a casing 10 having an upper part 11 in the form of an inverted hollow member, and having a lower part 12 comprising an upright hollow member, the said parts engaging each other along edges 11a and 12a respectively and constituting an enclosure for the power and driving mechanisms of the spotlight.

Preferably the casing part 11 has integral with it a mounting plate or bracket 13 whereby it may be secured to a supporting surface, as the side of an automobile body. Opposite the mounting plate 13 the casing part 11 has a tubular extension 14 rotatably carrying a shaft 15 which mounts an elbow-shaped fitting 16 on which is journaled a lamp head 17.

The lamp head 17, also herein termed a spotlight unit, may comprise a shell 18 carrying a reflector 19 and an electric bulb 20. The shell 18 may be mounted on a shaft 21 which is rotatable in the elbow fitting 16 whereby the lamp head 17 is rotatable about an axis X-X angularly disposed with relation to the axis Y-Y of the shaft 15.

The inner end of the shaft 21 mounts a bevel gear 22 which meshes with a second bevel gear 23 carried on a shaft 24 passing through the shaft 15. Shafts 24 and 15 which are relatively movable, have in common the axis Y-Y, and shaft 15 is as mentioned before, rotatable in the tubular extension 14 of the casing 10.

For the purpose of driving the shafts 21, 15 and 24, the latter two shafts have spur gears 25 and 26 respectively, meshing with pinions 27 and 28. Referring to Figs. 2 and 3, the pinions 27 and 28 are carried on shafts 29 and 30 which in turn carry worm wheels 31 and 32 meshing with worms 33 and 34 mounted on a common shaft 35, the worm 33 being loose on the shaft and the worm 34 rigid with the shaft as shown in Fig. 4.

At its center the shaft 35 carries a worm wheel 36 meshing with a worm 37 on shaft 38 of an electric motor 39 carried in the lower casing part 12 of the spotlight, Fig. 1. As seen in Fig. 4 the worm 33 is rigidly secured to a spur gear 40, which at all times meshes with a cooperable spur gear 41 rotatable on a shaft 42. The shaft 35 has rigidly secured to it adjacent the spur gear 40 a second and similar spur gear 43 which can also mesh with the gear 41. The spur gears 40, 41 and 43 constitute a clutch device, the gear 41 being axially slideable on the shaft 42 and being controlled by a collar 44 and arm 45 connected to a plunger 46 and core 47 of a solenoid 48. A compression spring 49 normally yieldably holds the core 47 and plunger 46 in the position shown in Fig. 2 wherein the gear 41 does not mesh with the gear 43. For this position, the gear 40 and worm 33 are not driven when the motor 39 is energized and operated. If, however, the solenoid 48 should be energized, this

will attract the core 47 and shift the gear 41 to the dotted-line position A shown in Fig. 4 wherein it will mesh with both the gears 40 and 43. As a consequence, the motor 39 will drive the worm 33.

It will be noted that when the solenoid 48 is not energized, energization of the motor 39 will result in driving of only the shafts 24 and 21, causing turning of the lamp head 17 about the axis X-X. When the solenoid 48 is energized, operation of the motor 39 will cause rotation of not only the shafts 24 and 21 but also the shaft 15, causing a turning of the lamp head 17 about the axis Y-Y. For this latter condition, when both the drive mechanisms are operative, rotation of the lamp head 17 about the axis X-X will cease for the reason that the shaft 24 will be driven in the same direction and have the same speed as the shaft 15. There will thus be no relative movement between shafts 24 and 15 and the bevel gears 22 and 23 will not rotate with respect to the elbow fitting 16, nor will the lamp head 17 turn about the axis X-X. In this connection it is pointed out that, for the dotted-line position of the gear 41 shown in Fig. 4, the pinions 27 and 28 will rotate in the same directions and at the same speeds, and will drive the spur gears 25 and 26 both in the same directions and at the same speeds. The ratios between the said pinions and gears are made equal.

I have found that with the above organization, merely controlling the solenoid 48 and the direction of rotation of the motor 39 will cause the lamp head or light unit 17 to be turned in either of reverse directions about either one of the axes X-X or Y-Y independently of the other. Thus, by such control of the solenoid and motor, an operator may from a remote point very easily and quickly, and with a minimum amount of skill, direct the beam of light from the bulb 20 to any desired spot, this being accomplished with but a single clutch device, and with simple and sturdy gearing which is reliable in its operation. Moreover, I have provided in each of the drive mechanisms for turning the lamp head 17 about the axes X-X and Y-Y a double worm reduction, resulting in a highly advantageous turn ratio between the motor shaft 38 and lamp head. This avoids undue load on the motor 39 and provides for a relatively slow turning movement of the lamp head, which prevents inadvertent overshooting of the mark or objective.

The worm drives comprising the worms 33 and 34 are irreversible, so that the lamp head 17 is held locked in any adjusted position; therefore it will not tend to swing downward or change position due to vibration or movement of the vehicle on which the spotlight is mounted. This makes it unnecessary to employ auxiliary frictional means to hold the lamp head in adjusted position, which means would be undesirable from the standpoint of the added expense as well as the added load imposed on the drive motor.

For the purpose of controlling the operation of the solenoid 48 and motor 39 a multi-position switch 59 is provided, Figs. 5 through 8. This switch comprises a tubular shell 51 adapted to be mounted on an instrument panel 52, the rear end of the shell carrying an insulating base 53 on which are mounted cooperable pairs of contacts 54, 55 and 56, 57, the said contacts being in the form of leaf springs and the pairs being located on opposite sides of the axis of the shell 51, extending along the inside of the shell. The

insulating base 53 also carries pairs of leaf spring contacts 58, 59 and 60, 61 extending into the shell on opposite sides of the axis. As shown in Fig. 7 the axial plane through the contacts 54 to 56 is at right angles to the axial plane through the contacts 58 to 60.

The switch 50 further comprises an elongate manually-operable electrically-conducting member 62 extending along the axis of the shell 51 between the pairs of contacts carried by the base 53. The inner end of the member 62 mounts a ball 63 carried in a socket 64 secured to a plunger 65 which is axially slidable in the base 53. The outer end of the plunger 65 carries a detent fitting 66 cooperable with a coil spring 67 having the shape of an annulus, which is held captive in a cage 68 secured to the base 53.

The member 62 mounts a knob 69 at its other end, and is axially movable together with the plunger 65 between the inoperative position shown in Fig. 6 to an operative position attained by shifting the member and plunger to the left, as viewed in this figure, until the detent spring 67 snaps to the other side of the fitting 66. The member 62 carries insulating collars 70 and 71, and metallic conducting collars 72 and 73 which are electrically connected together through the member. For the inoperative position of Figs. 6 and 7 the insulating collars 70 and 71 are in position to engage the leaf spring contacts as indicated; when the member 62 is shifted to the left to operative position, the conducting collars 72 and 73 take the places of the insulating collars of 70 and 71 and are cooperable with the said leaf springs.

At its forward end the shell 51 carries an escutcheon member 74 having a cruciform opening 75, and having helical coil springs 76 extending into the said opening and normally centralizing the member 62 in the opening.

The circuit diagram of the spotlight and control means therefor is shown in Fig. 5. The various parts of the control switch 50 are shown located within a broken rectangular outline 50a. The spot-light bulb 20 has one terminal grounded and the other connected by a wire 77 to an on-off switch 78 which is in turn connected by a wire 79 with the switch contact 61. The opposite switch contact 59 is connected by a wire 80 with a battery 81 which has its other terminal grounded.

The motor 39 has an armature 82 connected to ground through a wire 83. The motor also has field coils 84 and 85 provided with a common connection which is connected by a wire 86 with the armature 82. The remaining terminal of the field coil 84 is connected by a wire 87 with switch contacts 54 and 58; the remaining terminal of the field coil 85 is connected by a wire 88 with switch contacts 60 and 56. Switch contacts 55 and 57 are connected together, and by a wire 89 with one end of the solenoid 48 the other end of which is grounded. A jumper 90 is shown connecting together the two portions of the manually operable member 62 which are illustrated diagrammatically in Fig. 5.

Operation of the improved spotlight of the invention is as follows: When the switch 50 is in the inoperative position shown in Figs. 6 and 7, the circuit leading from the battery 81 will remain open. For this condition, actuation of the manually operable member 62 either up or down, or to one side or the other, will not cause operation of the spotlight. If, from the position of Fig. 6, the knob 69 of the member 62 (and the

member) should be pulled outward or to the left to operative position, this will cause the contacts 59 and 61 to be bridged by the conducting collar 73. Assuming that the switch 78 is closed, this will result in energization of the bulb 20. If now the knob 69 should be shifted upward as viewed in Fig. 6 (corresponding to moving it to the left when the switch is mounted on the instrument panel) this will cause the collar 72 to engage the leaf spring contact 58, and will result in energization of the field coil 84 and armature 82 of the motor 39, causing the motor to operate in one direction. Such operation will cause the pinion 28 to drive the spur gear 26 and cause turning of the shafts 24 and 21 of the lamp, resulting in a turning of the lamp head 17 about the axis X-X. If the knob 69 should be moved in the opposite direction or downward as viewed in Fig. 6 (to the right when the switch 50 is mounted on the instrument panel 52) then the leaf spring contact 60 will be energized, causing energization of the motor field coil 85 and armature 82, and causing a reverse rotation of the motor 39. This will result in the lamp head 17 turning in a reverse direction about the axis X-X.

Referring to Fig. 7, if the switch member 62 is moved upward it will result in the collar 72 engaging the leaf spring 55 and also result in engagement of the latter with the leaf spring 54. This will cause energization of the motor field coil 84 and of the solenoid 48, the latter being the first to be energized. The clutch gear 41 will immediately be shifted to the position of Fig. 4 and then the motor 39 operated, whereupon both of the shafts 15 and 24 of the spotlight will be turned at the same speed and in the same direction. This will cause the lamp head 17 to turn about the axis Y-Y, but will not cause the lamp head to turn about the axis X-X. If the switch member 62 should be shifted downward as viewed in Fig. 7, connection will be established between the collar 72 and the leaf springs 56 and 57, causing energization of the motor field 85 and the solenoid 48, and this will cause a reverse turning movement of the lamp head 17 about axis Y-Y. After completion of use of the spotlight, the light unit 17 may be returned to any desired storage position by shifting the knob 69 either up or down or to one side or the other, and the light may then be extinguished by pushing the knob inward to restore the switch parts to the position of Fig. 6.

In certain circumstances it may be found desirable to aim or direct the spotlight without the bulb 20 being energized; to accomplish this it is merely necessary, according to the above organization, to open the switch 78.

Another form of control switch for operating the spotlight is illustrated in Fig. 9. Four switch buttons 90, 91, 92 and 93, having the letters L, D, R and U respectively, are mounted on a plate 94 at the center of which an on-off switch 95 is carried. The buttons 90 and 92 are disposed respectively to the left and right of the switch 95, and the buttons 91 and 93 disposed respectively below and above the switch 95.

The on-off switch 95 may be connected to the wires 79 and 80 in the circuit of Fig. 5. The buttons 90 and 92 actuate switch contacts (not shown) which may be connected to the wires 87 and 88. The switch buttons 91 and 93 actuate contacts (also not shown) which may be connected to the wires 87, 88 and 89, all in the manner clearly illustrated in Fig. 5 whereby press-

ing of any one button 60, 91, 92 or 93 will control the lamp head 17 in the same manner as actuation of the switch knob 68 in the direction corresponding to location of the button.

Variations and modifications may be made within the scope of this invention and portions of the improvements may be used without others.

I claim:

1. In an electrically-controlled dirigible spotlight of the type having a metal casing, an electric motor in the casing, a lamp head including an electric bulb, mounted on the casing and driven by the motor, said head being movable about two non-parallel axes and being permanently geared to the motor for adjustment about one axis, and said spotlight having a solenoid in the casing, controlling disengageable gearing between the motor and lamp head to effect adjustment of the head about the other axis without changing adjustment about the one axis, the improvement which comprises providing a circuit therefor including ground connections between the casing, electric bulb, motor armature, and the solenoid; a pair of field coils in said motor, having a common connection which is joined with the ungrounded side of the armature; and separate leads from the unconnected sides of the solenoid, field coils, and electric bulb, passing out of the casing whereby a potential applied between the casing and individual leads or combinations of said leads will effect energization of the electric bulb, operation of the motor in forward or reverse directions, and gear connections between the motor and lamp head to provide adjustment of the latter about either of said axes.

2. In an electrically-controlled dirigible spotlight of the type having a metal casing, an electric motor in the casing, a lamp head including an electric bulb, mounted on the casing and driven by the motor, said head being movable about two non-parallel axes and being permanently geared to the motor for adjustment about one axis, and said spotlight having a solenoid in the casing, controlling disengageable gearing between the motor and lamp head to effect adjustment of the head about the other axis without changing adjustment about the one axis, the improvement which comprises providing a circuit therefor including ground connections between the casing, electric bulb, motor armature, and the solenoid; a pair of field coils in said motor, having a common connection which is joined with the ungrounded side of the armature; separate leads from the unconnected sides of the solenoid, field coils, and electric bulb, passing out of the casing; and selectively operable switch means to provide for connection of a potential first between the casing and electric bulb lead, and thereafter either between the casing and one or the other of the motor field leads, or between the casing and the solenoid lead and then between the casing and one or the other of the motor field leads.

3. In an electrically-controlled dirigible spotlight of the type having a metal casing, an electric motor in the casing, a lamp head including an electric bulb mounted on the casing and driven by the motor, said head being movable about two non-parallel axes and being permanently geared to the motor for adjustment about one axis, and said spotlight having a solenoid in the casing, controlling disengageable gearing between the motor and lamp head to effect adjustment of the head about the other axis without changing adjustment about the one axis,

the improvement which comprises providing a circuit therefor including ground connections between the casing, electric bulb, motor armature, and the solenoid; a pair of field coils in said motor, having a common connection which is joined with the ungrounded side of the armature; separate leads from the unconnected sides of the solenoid, field coils, and electric bulb, passing out of the casing; and selectively operable switch means to provide for connection of a potential between the casing and electric bulb lead, and either between the casing and one or the other of the motor field leads or between the casing and solenoid lead and one or the other of the motor field leads.

4. A dirigible spotlight comprising a spot-light unit and means for supporting the same for rotation about two axes at an angle to each other; a reversible motor; and mechanism for moving said spot-light unit, including gear means permanently connecting the unit to said motor to be moved in either direction thereby to provide a permanent drive therebetween for rotating said spot-light unit about one axis, and second gear means separate from the first gear means connecting said unit to said motor to move the unit about the other axis, said second gear means including means optionally actuated to cause said second gear means to be rendered operative to move the unit about said other axis.

5. A dirigible spotlight comprising a spot-light unit and means for supporting the same for rotation about two axes at an angle to each other; a reversible motor; and mechanism for moving said spot-light unit, including gear means permanently connecting the unit to said motor to be moved in either direction thereby to provide a permanent drive therebetween for rotating said spot-light unit about one axis, and second gear means separate from the first gear means connecting said unit to said motor to move the unit about the other axis, said second gear means including means normally disconnecting the drive between the unit and motor and manually operable means optionally actuated to cause said second gear means to be connected to the motor to move the unit about said other axis.

6. A dirigible spotlight comprising a spot-light unit and means for supporting the same for rotation about two axes at an angle to each other; a reversible motor; and mechanism for moving said spot-light unit, including gear means permanently connecting the unit to said motor to be moved in either direction thereby to provide a permanent drive therebetween for rotating said spot-light unit about one axis, and second gear means separate from the first gear means connecting said unit to said motor to move the unit about the other axis, said second gear means including means optionally actuated to cause said second gear means to be rendered operative to move the unit about said other axis, each of said gear means including an irreversible gear means permanently connected to the unit whereby the unit is locked in any adjusted position when not being driven.

7. A dirigible spotlight comprising a spot-light unit and means for supporting the same for rotation about two axes at an angle to each other; a reversible motor; mechanism for moving said spot-light unit, including gear means permanently connecting the unit to said motor to be moved in either direction thereby to provide a permanent drive therebetween for rotating said spot-light unit about one axis, and second gear

means separate from the first gear means connecting said unit to said motor to move the unit about the other axis, said second gear means including means optionally actuated to cause said second gear means to be rendered operative to move the unit about said other axis; and means connected to said motor and to said second gear means for controlling the movement of the unit including a device actuatable by an operator in the senses left, right, up and down, the left and right movement controlling the direction of rotation of said motor and movement of the unit by the first gear means about said one axis and the up and down movement controlling direction of rotation of said motor and operation of said second gear means to move the unit about said other axis.

8. A dirigible spotlight comprising a spot-light unit and means for supporting the same for rotation about two axes at an angle to each other; a reversible motor; mechanism for moving said spot-light unit, including gear means permanently connecting the unit to said motor to be moved in either direction thereby to provide a permanent drive therebetween for rotating said spot-light unit about one axis, and second gear means separate from the first gear means connecting said unit to said motor to move the unit about the other axis, said second gear means including means optionally actuated to cause said second gear means to be rendered operative to move the unit about said other axis; and means connected to said motor and to said second gear means for controlling the movement of the unit including a device actuatable by an operator in the opposite senses, the movement of the device in one sense controlling the direction of rotation of said motor and movement of the unit by the first gear means about said one axis and the movement of the device in the opposite sense controlling direction of rotation of said motor and operation of said second gear means to move the unit about said other axis.

9. A dirigible spotlight comprising a spot-light unit and means for supporting the same for rotation about two axes at an angle to each other; a reversible motor; and mechanism for moving said spot-light unit, comprising first gear means including angularly related gears respectively rotatable about said axes and permanently connecting the unit to said motor to be moved in either direction thereby to provide a permanent drive therebetween for rotating said spot-light unit about one axis, and second gear means separate from the first gear means connecting said unit to said motor to move the unit about the other axis, said second gear means including means optionally actuated to cause said second gear means to be rendered operative to simultaneously drive the unit from said motor to move the unit about said other axis, the ratio between the first and second gear means causing movement of the unit about the one axis to cease during the simultaneous operation of the second gear means to move the unit about said second axis.

10. A dirigible spotlight comprising a casing; an elbow rotatable on the casing about a substantially horizontal axis; a lamp head carried by the elbow and rotatable thereon about an axis non-parallel with said horizontal axis; mounting means for securing the casing to a support; a reversible electric motor carried by the casing between said elbow and mounting means; drive means connecting the lamp head and motor to form a permanent drive therebetween for rotat-

ing the lamp head with respect to the elbow; gear means connecting the elbow to the motor to simultaneously drive the elbow from the motor for rotation about said horizontal axis, said gear means having a ratio with respect to said drive means connecting the lamp head to the motor that rotation of the lamp head with respect to the elbow ceases regardless of the direction of turning of the motor and including means for breaking the driving connection between the elbow and motor; means under the control of an operator for rendering operative or inoperative the means breaking the driving connection in the gear means; and means under the control of the operator, for reversing said motor.

11. A dirigible spotlight comprising a casing; an elbow rotatable on the casing about a substantially horizontal axis; a lamp head carried by the elbow and rotatable thereon about an axis non-parallel with said horizontal axis; mounting means for securing the casing to a support; a reversible electric motor carried by the casing between said elbow and mounting means; drive means connecting the lamp head and motor to form a permanent drive therebetween for rotating the lamp head with respect to the elbow; gear means connecting the elbow to the motor to simultaneously drive the elbow from the motor for rotation about said horizontal axis, said gear means having a ratio with respect to said drive means that rotation of the lamp head with respect to the elbow ceases regardless of the direction of turning of the motor and including clutch means for breaking the driving connection between the elbow and motor; and remote control means connected to said motor and clutch means for rendering operative or inoperative the clutch means and for controlling the direction of rotation of said motor.

12. A dirigible spotlight comprising a casing; an elbow rotatable on the casing about a substantially horizontal axis; a lamp head carried by the elbow and rotatable thereon about an axis non-parallel with said horizontal axis; mounting means for securing the casing to a support; a reversible electric motor carried by the casing between said elbow and mounting means; drive means connecting the lamp head and motor to form a permanent drive therebetween for rotating the lamp head with respect to the elbow; gear means connecting the elbow to the motor to simultaneously drive the elbow from the motor for rotation about said horizontal axis, said gear means having a ratio with respect to said drive means that rotation of the lamp head with respect to the elbow ceases regardless of the direction of turning of the motor and including a disengageable gear for breaking the driving connection between the elbow and motor and means for moving said gear; and means under the control of an operator for rendering said disengageable gear operative or inoperative to drive the elbow from said motor.
